UNITED STATES PATENT OFFICE.

GEORGE W. EDWARDS, OF TOLEDO, OHIO, ASSIGNEE OF ONE-TENTH TO JAMES P. GILLIGAN, ONE-TENTH TO CHRISTENA GILLIGAN, ONE-TENTH TO CHARLES C. MONAHAN, ONE-TENTH TO HERMAN F. WIDMAN, AND ONE-TENTH TO FRANK C. GARBE, ALL OF TOLEDO, OHIO.

AUTOMATIC TRAIN-STOPPING DEVICE.

Application filed June 27, 1921. Serial No. 480,590.

To all whom it may concern:

Be it known that I, GEORGE W. EDWARDS, a citizen of the United States of America, residing at Toledo, in the county of Lucas and State of Ohio, have invented certain new and useful Improvements in Automatic Train-Stopping Devices, of which the following is a specification.

My invention relates to an automatic train stopping device and aims to provide a device of this nature which fits in with the airbrake equipment of a train and which necessitates very little mechanism in addition to such equipment in order to attain the desired results. The apparatus provided by me is peculiarly simple and efficient in that it comprises merely a portable flagging block or a permanent tripping device, operated in connection with the regular block system or from signal towers, piston and cylinder construction of the type commonly utilized in airbrake systems, and valve controlled piping that may be applied without difficulty.

Furthermore, my invention contemplates the use of a trip valve having a hollow handle and a locking device in combination therewith and so arranged that when the operating valve handle of any oncoming train engages with the flagging block, the said valve handle will either be tripped and locked or the hollow handle broken. In either case, the oncoming train will be positively stopped and the engineer or some one from the train will be compelled to descend from the train to the ground to reset appropriate mechanism in order to release the brakes and to place the engine parts in condition for further operation.

A still further object of my invention consists in providing means for resisting closing of the throttle and with varying degrees of resistance, so that the throttle will only be moved toward closed position when the air pressure reaches a predetermined amount. This structure is such that either complete closure or any desired closure of the throttle can be attained at will.

I have further provided a means to ensure that the branch pipe which carries my trip-

ping valve will be entirely free from moisture of condensation at all stages of operation. Furthermore, I have provided a means that will practically ensure a report 55 of every accident or stopping of the engine due to the operation of the tripping valve.

My device is of such a nature that the flagging block may be carried to a point back of or in front of a stalled train or in 60 front of any approaching train and so applied to a rail that any oncoming train properly equipped will be positively stopped. The same results will follow if a permanently located tripping device at the entrance to a block or at some distance from 65 a derail or other dangerous point is "set" from a signal tower by an operator.

The preferred embodiment of my invention is shown in the accompanying drawings wherein similar characters of reference designate corresponding parts and wherein

Figure 1 is a side elevation of a locomotive showing my invention attached in proper relation thereto. It illustrates the 75 trip valve, the small cylinder in the cab and the portable flagging block.

Figure 2 is a detail view showing my automatic mechanism for closing the throttle and the properly tensioned spring contained 80 therein.

Figure 3 is a side elevation of the portable flagging block.

Figure 4 is a detail view of the trip valve showing the safety locking device thereon. 85

Figure 5 is a longitudinal section on line A—A of Figure 4.

Figure 6 is a detail view of an operating device of modified form.

In the drawings, my invention is shown as 90 comprising a pipe 1 connected through an elbow 2 to the airbrake pipe system 3 of the train. This pipe passes upwardly from the pipe 3 and then downwardly over the steam chest and through the cylinder lagging A. 95 There is always more or less moisture in compressed air. This moisture condenses, especially in cold weather, and tends to flow to the lowest level. An important aspect of this invention arises from the fact 100 that the upward loop 2 prevents any condensed moisture in the main pipe from pass-

ing into pipe 1, and pipe 1 passing through the cylinder lagging prevents any moisture accumulated in pipe 1 from freezing and thus damaging the pipe or making the valve 5 inoperative. The pipe 1 is provided with a cutout cock 6 operable by hand. This cock 6 is normally open and is to be closed only in case the operating valve 5 at the lower end of this pipe 1 becomes damaged.

10 By closing this cock 6 the train could be operated until repairs could be made.

The operating valve 5, attached to the lower end of the branch pipe 1, consists of a body 7, a vertical inlet port 8, a tapered 15 outlet port 9 and a horizontal tapered socket or valve seat 10. Fitting and turning in this tapered socket 10 is a hollow tapered valve handle 11, the outer end 12 of which is bent at right angles to 20 the horizontal tapered portion 11 and containing in this tapered portion 11 an inlet port 14 which registers with the main inlet port 8 when the valve handle extends vertically downward as shown in Fig. 5. A 25 lock nut 47 on the end of the tapered valve 11 holds the valve on the valve seat 10 by means of a spring 48. A cover 49 adapted to be secured to the boss 50 of the valve body 7 serves as a protection for the lock nut 47 30 and spring 48.

Attached to and extending from this valve handle 11 is an arm 13 the outer end of which rides on an arcuate shaped leaf spring 15. This leaf spring is fastened at its 35 base to the body extension 16 and extends upwardly and close to the stop 17. An ear 18 extending out from the tripping arm 12 of the valve handle 11 registers with the ear 19, extending out from the body of the 40 valve, when said valve handle is in its downward normal position. In this normal position of the valve handle, the two ears 18 and 19 are preferably linked by a seal 20. The tripping arm 12 extends down a sufficient 45 distance to ensure contact with a flagging block 21.

This flagging block 21 is of such construction that it will extend about eight (8) 50 inches above the rail 22 and is desirably located outside of the rail about 27 inches from the inside of the rail to the center line of the block. The base of the block 21 extends along the edge of a tie 23 and the end of this base is bent upwardly in hook form 55 to fit over the inner flange of the rail as shown in Figure 3. A clamp 24 and nut 25 ensures a solid fastening of the flagging block 21 to the rail and the plate 26 attached to the base of the block 21 holds the 60 block in its proper relation to the rail.

In the operation of this automatic mechanism, the proper location of the flagging block 21 will cause this block 21 to engage 65 with the tripping arm 12 of a moving train. The moving of the tripping arm 12 of the

valve handle 11 will rotate the valve stem 10, release the compressed air through the port 9 and thus automatically effect lowering of the pressure in the brake pipes. This lowering of the pressure causes shifting of 70 the triple valve 27 and allows the compressed air in the tank 28 to expand into the brake cylinder 29, thus setting the brakes. The hollow valve handle 11, having a port opening 14, will contain compressed air 75 while the tripping arm is in its normal downward position. Thus, if this hollow tripping arm 12 should be broken, from engagement with the flagging block 21 or 80 from any other cause, the compressed air would escape through the broken handle and likewise effect a lowering of pressure in the 85 brake pipes.

In case the flagging arm 12 is rotated, the connected arm 13 (Figure 4) will ride 85 along the spring quadrant 15 until it strikes the stop 17 when it will slip over the upper end of the spring 15 thus causing the valve handle to be locked and the valve to remain 90 open until the engineer descends to the ground and releases the same. Furthermore, a turning of the valve handle and the subsequent breaking of the attached numbered seal, or the breaking of the valve handle, 95 will necessitate the making of a report by the engineer and the reasons therewith.

It will be evident that the breaking of the seal and the subsequent necessitated report 100 is an important feature in that it will be instrumental in causing the engineer to operate the train with the greatest possible caution and safety.

In connection with this mechanism, I have provided a cooperating mechanism for 105 automatically moving the throttle toward closure (see Figures 1 and 2). It consists of a branch pipe 30, connected to and passing upwardly from the airbrake pipe connecting the tank 28 and cylinder 29, a small cylinder 31 connected to the branch pipe 30 at its upper end and a piston 32 working in this cylinder 31 connected to the throttle lever 40 by means of its rod 33 and a flared sleeve 34. Connecting the sleeve 34 to the 110 throttle rod 41 is a latch 36 fulcrumed to the throttle lever at 37. The throttle rod 41 co-operates with the serrated quadrant 39 and is held in any adjusted position with relation thereto by means of the dog 38. Regulating the motion of this throttle lever 40 and contained in the cylinder 31 is a 115 properly tensioned spring 42 desirably made to withstand about forty-five (45) pounds pressure. The flared sleeve 34 contains a cushion spring 35 in the small end 120 adjacent the throttle lever 40.

In the operation of the cooperating throttle closing mechanism, the opening of the operating valve 5 and the subsequent lowering 130 of pressure and shifting of the triple valve

27 will not only allow expansion of the compressed air in the brake cylinder 29 but will simultaneously force the high pressure air through the brake cylinder 30. This accumulated pressure on the piston 32 will force the piston rod 33 forward against the definite pressure exerted by the spring 42. This forward motion of the piston striking the cushioned sleeve 34 will cause the 5 fulcrumed latch 36 to be pressed downward. The subsequent downward motion of the throttle rod 41 will withdraw the dog 38 from the quadrant 39. Thus, further motion by the piston rod 33 closes the throttle 10 lever to fixed position as determined by the strength of the resisting spring 42. This position is preferably that of a "drifting throttle" or slightly open valve so that a small quantity of steam flows to the cylinders. Upon closure of the operating valve 5 or cutout cock 6, the triple valve 27 is closed by the resulting increased pressure in the main airbrake line and the tensioned spring 42 will automatically force the piston 20 back to normal position.

The modified operating device 43 is designed to replace, if desired, the preferred operating device attached to the pipe 1 as shown in Figures 4 and 5. It consists of 30 a section of standard pipe adapted to be attached to the lower end of the branch pipe 1 as at 46 in Figure 6. This pipe 43 depends downward a sufficient length to ensure contact with the flagging block 21 and is provided at the bottom end thereof with a drain plug 45. It contains at a 35 point adjacent the branch pipe 1 a hacksawed groove 44 encircling the pipe and of sufficient depth to ensure a positive breaking of the pipe at this point when struck by the flagging block.

It should be understood that this modified operating pipe may be used either temporarily or permanently and may be of any suitable material such as iron, steel or glass, the breaking of which, by engagement with 45 a flagging block, will automatically release the compressed air and thus effect a lowering of the pressure in the brake pipes.

The simplicity of my invention is unusual in that results are attained by the mere addition of two branches to the air-brake pipe system and a piston working 50 against a properly tensioned spring for operating the throttle lever. This closing of the throttle lever and the setting of the brakes is attained by a flagging block either portable or permanent.

The portable flagging block is particularly advantageous because, in the event that a train becomes stalled, a brakeman can readily carry this block forward and one rearward of the train on a single track line and rearward on a double track line, and by 55 setting it be sure that any oncoming train

will be automatically stopped. Nothing will depend on the eyesight of the engineer, foggy weather conditions, or any obstructed view of the flagman. Furthermore, after a train is once stopped by my device, the 70 engineer cannot restore running conditions while in his cab but must descend to the ground. My device gives the conductor full control of the train for by opening the conductor's valve, the brake pipe pressure 75 is lowered causing the brakes to be applied and the throttle automatically closed. The same results will follow if the train breaks in two.

It will be obvious that with my apparatus, whenever pressure in the air brake system is reduced sufficiently to set the brakes, regardless of the cause, the throttle will be moved toward closed position. The extent of such movement may be varied by 80 varying the strength of the spring 42. It will also be obvious that with my device the air control lever is not affected by my tripping operation but the brakes are set without the application of any force to such 85 lever.

Having thus described my invention, what I claim is:

1. In an automatic train controlling system, means operable by a trip for setting 90 the brakes and closing the throttle, said means comprising a trip operated valve, a branch pipe connecting said trip operated valve to the system and a vertical loop connecting said branch pipe to said system for 95 preventing any condensed moisture from passing into said branch pipe.

2. The combination with the air brake system of a locomotive; of a pipe connected into the main air line of said system and extending downwardly therefrom and through the lagging of the locomotive cylinder, the said pipe connecting with the upper portion of the said air line whereby a loop is formed, and a detent actuated valve on 100 the lower end of said pipe.

3. In a detent operated valve for train control systems; a valve casing connected in the air line of said system, a hollow valve plug in said casing adapted when in a certain position to vent the system by passage of the air through said plug, the said plug being extended beyond the casing to provide a frangible handle and hollow throughout its length, and the said plug having an opening therein at all times in communication with said system.

4. In a detent operated valve for train control systems; a valve casing connected in said system, a handle for operating said valve, an arm connected to said handle and movable therewith, a spring secured at one end to said casing and pressing against said arm, a stop limiting the travel of said arm, and the free end of said spring terminating 120 125 130

inwardly from said stop a distance slightly greater than the breadth of said arm at its point of contact with said spring.

5. In an automatic train controlling system the combination with the air brake system of a pipe connected into the main air line of said system, and a trip operated valve connected to said pipe for automatically

stopping the train, said pipe passing through the lagging of the locomotive cylinder between its connection to the main air line and said trip operating valve. ¹⁰

In testimony whereof I hereby affix my signature.

GEORGE W. EDWARDS.
